LEWIS IRVINE THOMPSON, OF PORTLAND, OREGON.

MACHINE AND PROCESS FOR SEPARATING THREADS FROM FABRIC.

Application filed April 28, 1926. Serial No. 105,109.

My invention relates to devices for separating the threads from woven or knit fabrics in order that the fibers may then be separated from the threads and reworked, 5 without being so much ground up or injured as they are by what are known as rag picking machines.

It is my purpose to provide a machine which shall approximate the action of the 10 thumb and forefinger in teasing or coaxing the threads from a piece of cloth or other fabric.

It is not my purpose to seize, pinch or hook into the material, whereby it will be 15 torn and broken, but by a gradually progressive plucking action, to separate the thread from the cloth.

I accomplish this by feeding the cloth or other fabric in one or more layers which are 20 laid substantially flat upon a feed table and then passed through feed rolls, about which rolls it does not wind. The cloth need not be fed so that some threads are parallel with the rolls, and others at right angles 25 thereto as my machine works better if the cloth is fed at an angle.

When the cloth leaves the feed rolls, its edge is steadily advanced until such edge comes in contact with rapidly revolving 30 arms preferably forming part of star shaped discs which revolve in opposite directions, the arms of the respective discs passing substantially between each other whereby they have a tendency to take hold 35 of the edge of the fabric.

If the adjoining edges of these arms were hooked, or of some other form, or if the arms of the two sets touched each other or were too close together, there would be 40 a shearing or cutting action which I do not desire.

I therefore round the outside edges of the arms and allow a substantial space between adjoining discs so that while adjacent overlapping arms will catch a thread between them, they will not hold it too tight but will permit it to slip either to the front, to the back or sideways.

This gives a soft teasing action and where 50 the cloth is fed at an angle so that one end of any particular thread is loosened up before the other, that end is repeatedly pulled and slips sideways between the arms until finally it is either pulled apart or pulled 55 out.

The continual rubbing and pulling of the disc arms and the air currents tend to straighten, untwist, expand and soften the threads. This is probably assisted by the electricity set up by the rubbing of the discs 60 on the threads.

In the drawings, Fig. 1 is a side elevation showing a machine of my construction without clearer discs.

Fig. 2 is a sectional elevation of the type 65 of machine with clearer discs shown in Fig. 5 but viewed from the side shown in Fig. 1 opposite that shown in Fig. 5.

Fig. 3 is a diagrammatic sectional view as from the left of the line 3—3 of Fig. 2. 70

Fig. 4 is a diagrammatic view from the top of part of the plucking discs, the bottom feed roll and a part of the edge of a piece of cloth.

Fig. 5 is an elevation of a machine having 75 clearer discs from the opposite side to that shown in Fig. 1.

Fig. 6 is a diagrammatic detail elevation showing the action of the plucking disc arms on the thread.

Fig. 7 is an enlarged detail of the end 80 of a thread which has passed through my machine.

In the drawings, 10 represents the base of my preferred type of machine and 11 represents the frame while 47 indicates the casing in general while 42 indicates that part of the casing which surrounds the blower 41 carried by shaft 39 on a stand 40, such blower causing a current of air to issue out of the mouth 85 43, the air being carried in through, between and around the star shaped discs A and B.

The cloth 25 in one or more flat thicknesses is laid on the table 26 and passed between the fluted feed rolls 27, 27, which are driven at a 90 much slower surface speed than the discs A and B.

Power may be applied in any usual way to shaft 13 which carries gear 23 which meshes with gear 24 on shaft 14, which shaft 14 also 100 carries a worm 35 in engagement with gear 34 on one end of shaft 32 carried centrally in bearing 33. Worm 31 is carried on the other end of shaft 32 and slowly drives gear 30 which in turn engages gear 28 carried by 105 shaft 29 which carries bottom roll 27, and a gear not shown which engages another gear 129 carried by top fluted roll 27.

The surface speed of these feed rolls 27, 27 110 is therefore slow compared with the high

speed of the star shaped discs A and B which are formed respectively with the arms 61 and 71, having the depressions 60 and 70 between them, and having the outer ends preferably 5 concave at 63 and 73 while the outer edges 62 and 72 are preferably rounded.

The sizes may be varied at will but I find discs about twelve inches in diameter each carried by a shaft about two and one half 10 inches in diameter, and each disc from $\frac{1}{2}$ " to $\frac{1}{8}$ " thick serves my purpose to good advantage.

The arms of these discs A and B intersect, or overlap, preferably several inches, or 15 whatever amount seems to be suitable for the class of material to be operated upon, and I prefer to have a space between the respective arms of the two discs equal to about 20 their thickness, and greater than the diameter of the threads of the material to be acted upon.

I have endeavored to indicate in Fig. 6 the action which I believe takes place on each particular thread 48 whether it be warp or 25 filling when it reaches the forward position at 49.

As it is advanced by the feed rolls, it takes a position successively as shown by the dotted circles, and as it advances, it is struck 30 successively by a number of arms 61 and 71 or rather by their rounded faces 62 and 72.

As the first contact of the rounded corners 62 and 72 with a thread such as 49, which is being advanced from among those indicated 35 in Fig. 2 by 48 which are still held firmly by the crossed warp threads 50 and 54, may be with the forward curved surface of such thread 49, the tendency if anything may be to force it back.

40 As this thread is steadily being advanced, when it arrives at the position shown at 149, the relative action of the arms at 62 and 72 is indicated by the lines of long dashes X, X, and as it still further advances to the position 249, the action tends more and more to force it forward as to the position of the thread 83 which is acted upon by the arms A and B which have arrived at the position shown by the lines of short dashes Y, Y.

50 As it is practically impossible to feed cloth at precisely right angles or parallel to the feed rolls, one end of each thread will be loosened before the other end, and the action just described will cause this end such as 55 shown at 84 or 81 in Figs. 2, 3 and 4 to be carried forward between arms 61 and 71, but as it is held also at the cloth, it will be pulled through the open spaces between 60 and 70, and bent back as at 85 and 82, until as shown 60 at 87 in Fig. 4, it streams out between adjoining arms 61 and 71, and is finally pulled apart.

51, 51, indicates the second bend in each thread at the edge of the cloth.

65 In Fig. 3 I have indicated successively the

arms 61, 61, from right to left by 89, 91, 93, 95, and in similar series, the alternating overlapping arms 71 by 90, 92, 94, 96.

It will be seen that the end 84 of thread 83, or any other similar thread, will first be 70 pulled through between the arms 90, 91, 92, and when it is again caught, as has been thread 80, the end 81 will be pulled through as between the arms 92, 93, 94, 95, and so on 75 successively.

When it is finally streaming out as shown at 87, it may be caught as a warp thread 54 is shown as caught in Fig. 2, around an arm, and it will be pulled apart.

As shown in Fig. 7, in every case there 80 is a pulling apart action so that the end 88 of each thread, whether warp or filling, is fluffy and not clean cut.

Besides this the continual rubbing of adjoining arms against opposite sides of any 85 particular thread, either tends to twist or untwist the thread, but as it is easier to untwist than to twist, this action helps to untwist each thread.

There is also a powerful drawing action 90 caused by the movement of the adjoining arms on the thread, and a powerful current of air which rushes through, and there is also static electricity generated between the fiber and the metal, especially if the fiber 95 is wool.

The result of this is that each thread is partly unwound, straightened and loosened up whereby it can afterwards be more readily separated into its fibers.

The action on knit goods is similar, the tendency of the stroking action of my revolving arms being to pull or draw each thread up to the point where it will eventually break or be pulled apart.

As shown, I prefer to use on each shaft 13 one or more collars or sleeves such as 15 and 17, and the same on the shaft 14, for by making these shafts larger the tendency 110 for the ends of the thread to wind up is reduced.

I prefer however, as shown in Figs. 2, 3 and 6, to have a larger casing and to use two rotary clearers F and G, each of which has star shaped arms 18 or 19, and each of 115 which is carried by a shaft such as 113 or 114, on which there may be a collar such as 117, the width of the arm such as 18 and 19 being sufficient to fill in the space between two adjoining arms such as 71 or 61, as clearly shown in Fig. 3, and the position of these clearer discs F and G being such, and the length of the arms being such that they reach down almost to the sleeves or collars 17, 17 respectively, of shafts 13 and 14.

These discs F and G are driven in such a direction that their respective arms will tend to plow off or scrape and carry forward any waste which accumulates on sleeves 17, 130 17, and throw it into the fan 41.

They are therefore caused to revolve in the direction of the arrows through the medium respectively of sprocket 100 carried by shaft 13 at the end opposite to gear 23, chain 101, sprocket 102 on shaft 113, and by sprocket 104 carried by shaft 14, chain 105 and sprocket 106 carried by shaft 114.

I claim:

1. In a machine for separating threads from fabrics, the combination of feed rolls; with two series of loosely interlocking or overlapping star shaped plucking discs revoluble in opposite directions, the arms of each disc being rounded, and the line of first intersection of the arms being opposite the nip of the feed rolls; and two star shaped clearer discs each closely interlocking or overlapping a plucking disc and filling the space between its adjoining arms and revoluble in the same direction with said plucking disc.

2. In a machine for separating threads from fabrics, the combination of feed rolls; with two series of loosely interlocking or overlapping star shaped plucking discs revoluble in opposite directions, the arms of each disc being rounded; and two star shaped clearer discs each closely interlocking or overlapping a plucking disc and filling the space between its adjoining arms and

revoluble in the same direction with said plucking disc.

3. In a machine for separating threads from fabrics, the combination of feed rolls; with two series of loosely interlocking or overlapping star shaped plucking discs revoluble in opposite directions, the arms of each disc being rounded.

4. The method of separating threads from fabrics which consists of advancing the edge of the fabric so that it will repeatedly be engaged by upper and lower members which successively exert a loose pinching and pulling action on the threads thereof.

5. A machine for separating threads from fabrics which comprises feed rolls and proximate the delivery side thereof, two series of overlapping star shaped discs revoluble in opposite directions, the arms of each disc being cut off and rounded, the first crossing points of the arms of the two series as the discs revolve being opposite the nip of the feed rolls.

6. In a machine for separating threads from fabric, the combination of feeding mechanism; with two series of loosely interlocking or overlapping star shaped plucking discs revoluble in opposite directions.
